(57) **CLAIM**

The ornamental design for a combined adjustable jock cup pouch and pants, as shown and described.

DESCRIPTION

FIG. 1 is a front elevational view of a combined adjustable jock cup pouch and pants showing my new design;

FIG. 2 is a back elevational view thereof;

FIG. 3 is a side elevational view thereof; the undisclosed opposite side being a mirror image thereof;

FIG. 4 is a top plan view thereof; and,

FIG. 5 is a bottom plan view thereof.

The broken lines on the surface of the garment in FIGS. 1-5 represent stitching.

The broken lines representing portions of the human form are included for the purpose of illustrating environmental structure only and form no part of the claimed design.
